US00D379231S

United States Patent [19]
Ungari

[11] **Patent Number:** **Des. 379,231**
[45] **Date of Patent:** ****May 13, 1997**

[54] MEDICAL ULTRASONIC IMAGING SYSTEM

[75] Inventor: **Joseph L. Ungari**, Everett, Wash.

[73] Assignee: **Advanced Technology Laboratories, Inc.**, Bothell, Wash.

[**] Term: **14 Years**

[21] Appl. No.: **29,613**

[22] Filed: **Oct. 12, 1994**

[51] LOC (6) Cl. **24-01**

[52] U.S. Cl. **D24/160**

Primary Examiner—Stella Reid

[57] **CLAIM**

The ornamental design for a medical ultrasonic imaging system, as shown and described.

DESCRIPTION

FIG. 1 is a front perspective view of a medical ultrasonic imaging system of the present invention;

FIG. 2 is a rear perspective view thereof; and,

FIG. 3 is an enlarged fragmentary perspective view of the keyboard thereof.

1 Claim, 3 Drawing Sheets
